UNITED STATES PATENT OFFICE.

GROVER F. BEHRINGER, OF DEFIANCE, OHIO, ASSIGNOR TO THE DEFTANCE PRERESSED STEEL COMPANY, OF DEFIANCE, OHIO, A CORPORATION OF OHIO.

BOTTLE-CRATE AND ADAPTER THEREFOR.

1,143,166.

Specification of Letters Patent. Patented June 15, 1915.

Application filed December 5, 1912. Serial No. 735,154.

To all whom it may concern:

Be it known that I, GROVER F. BEHRINGER, a citizen of the United States, residing at Defiance, in the county of Defiance and State of Ohio, have invented certain new and useful Improvements in Bottle-Crates and Adapters Therefor, of which the following is a specification, reference being had therein to the accompanying drawings.

This invention relates to boxes or crates for storing and shipping bottles for containing liquids, such as milk or beer.

The invention relates more particularly to devices for use in connection with bottle-holding boxes or crates to change the size of the bottle cells so that bottles of different sizes may be held in the same box or crate.

Therefore, the principal object of the invention is to provide devices, to be termed adapters, which can be temporarily placed within the cells of a bottle crate to reduce the effective size of the cells so that smaller bottles may be held.

Another object is to provide adapters having certain advantageous structural characteristics.

A further object is to provide in combination a box having certain structural features and adapters constructed to coöperate with the box structure in a peculiar manner.

In the accompanying drawings I have shown one embodiment of my invention, but it will be understood that so far as many of the features of my invention are concerned many changes and modifications may be made.

Of the drawings, Figure 1 is a longitudinal sectional view showing in combination a box and adapters embodying my invention. The view is taken along the line 1—1 of Fig. 2. In this view one of the cells is shown without an adapter and in this cell there is shown a bottle of the size for which the box is normally intended. In another cell is shown a bottle of a smaller size. Fig. 2 is a cross sectional view taken along the line 2—2 of Fig. 1. In this view one of the cells is shown without an adapter and in this cell there is shown a bottle of the size for which the box is normally intended. In one of the other cells is shown a bottle of a smaller size. Fig. 3 is a plan view of the box shown in Figs. 1 and 2. In this view the bottle-retaining plate is omitted and adapters are shown in all of the cells. Fig.

4 is a perspective view of one of the adapters.

The box which I have shown in the drawings for purposes of illustration is made up of sections of sheet metal suitably secured together and properly reinforced. It will be understood, however, that my invention is not necessarily limited to boxes of this type but may be used in connection with boxes formed of other materials, such as wood. It will be further understood that even when metal is selected as a material there may be wide variation from the particular construction which I have illustrated.

In the drawings 1—1 represent the end walls of the box and 2—2 represent the side walls. The side and end walls are suitably crimped together at the corners and are reinforced at the top edges by means of a rod 3 which is inclosed in suitably formed beads. 75 At the bottom of the box there are two wire rectangles 4 and 5. These rectangles are held in place by means of metal strips 6—6 which are crimped with the lower edges of the end and side walls to form a flange 7 80 around the box. At their adjacent edges the two wire rectangles 4 and 5 are connected by means of a metal strip 8. The wire rectangles 4 and 5 project downward below the bottom horizontal plane of the 85 flange 7 and thus serve as a "stacking" flange. The rectangles are of such size that when one box is placed upon another the rectangles of the upper box will project into the lower box and engage the upper edges 90 thereof to prevent lateral displacement of the upper box with respect to the lower box.

The bottom of the box comprises longitudinally extending wires or rods 9—9 which are bent at their ends and seated in beads 95 formed at the edges of metallic strips 10—10, these strips being crimped into the parts of the flange 7 at the ends of the box.

Within the box there is provided a cellular structure which may be of any one of several forms but which is preferably similar to that shown in the drawings. As shown, this cellular structure comprises a series, in this case three, of longitudinal sheet metal partitions 11—11, and a series, 100 in this case four, of transverse metallic partitions 12—12. Preferably the partitions of the two series terminate at their upper edges in the same horizontal plane and the upper edges may be beaded for purposes of 110

reinforcement. Preferably the lower edges of the transverse partitions extend downward to a plane below the lower edges of the longitudinal partitions and are bent to form laterally projecting flanges 13-13. 5 Immediately above these flanges 13-13 are apertures through which the bottom wires or rods 9-9 extend. The flanges 13-13 serve not only to reinforce the partitions against lateral distortion but also serve to 10 give firm supports for the central parts of the rods. Preferably the lower edges of the longitudinal partitions 11-11 are beaded as indicated at 14-14. 15 15 is a retaining plate which serves to lock the bottles in place in the crate and to prevent their falling out when the crate is inverted to be placed in a bottle-washing machine or for any other purpose. This retaining plate is reinforced at its edges and 20 is provided with openings registering with the bottle cells, these openings being adapted to receive the necks of the bottles. In order to detachably secure the retaining plate, locking devices are provided. Those 25 which I have illustrated comprise latches 16-16 pivoted to the end walls of the crate and adapted to extend through suitable apertures in the end walls. The latches are 30 held in operative positions by means of springs 17-17. It will be clear that these locking devices normally serve to prevent the removal of the retaining plate and consequently of the bottles, and it will also be 35 clear that these locking devices can be easily released manually to permit the retaining plate and bottles to be removed.

In one cell in Figs. 1 and 2 I have shown 40 a bottle of the size for which the box is normally intended. In each of the other cells I have shown adapters 18-18 which reduce the available space within the cells and adapt them for holding bottles of a smaller size such as are shown in the drawings. 45 These adapters are readily removable and may be constructed in any of a variety of ways. The construction which I have shown, however, has certain marked advantages.

Referring especially to Fig. 4 it will be 50 observed that an adapter of the sort illustrated comprises two strips of metal 19 and 20 which intersect at right angles and are connected together at the point of intersection preferably by means of a rivet. Each 55 end part of each strip is, at a suitable distance from the point of intersection, bent upward as indicated at 21. At the upper ends of each vertical sections 21-21 there are short outward-extending horizontal sections 22-22 which connect with downward extending vertical sections 23-23, 24-24. The sections 24-24 are considerably longer than the sections 23-23, for a purpose 60 which will presently appear. The adapter 65 is of such a size that its inner walls 21-21

will engage a bottle of the smaller size to be carried in the box and that its outer walls 23-23 and 24-24 will engage the walls of a cell of the box.

Referring again to Figs. 1 and 2 it will 70 be observed that the longer sections 24-24 of each adapter extend downward to engage with and rest upon either one of the strips 10-10 at the ends of the box or one of the flanges 13-13, at the lower edges of the partitions 12-12. The shorter sections 13-13 are of such length that they engage with the beads 14-14 at the lower edges of the partitions 11-11 and are in this way supported. The top parts 22-22 of the adapters 80 lie just below the beads at the tops of the partition walls 11-11 and 12-12 and in this way the adapters are held against accidental displacement.

The adapters are formed of resilient 85 metal and on this account they can be easily inserted into or removed from the cells. The resiliency of the adapters causes them to closely grip the sides of the cells, and it will be clear that only by springing 90 them inward can they be removed past the beads at the upper edges of the partitions.

From the foregoing description it will be clear that I have provided means whereby a box normally intended for bottles of one 95 size can be easily adapted for holding bottles of a smaller size. Prior to my invention it has been necessary for a user of bottle boxes or crates of this general type to have a complete stock of boxes to correspond to 100 each size of bottles intended to be handled. However, it is frequently difficult if not impossible for a user or dealer to determine definitely in advance just what proportion of his goods must be supplied in bottles of 105 one size and what proportions in bottles of another size. For instance, if the liquid to be contained in the bottles is milk, the dealer cannot with certainty tell in advance at the time of placing his orders for boxes, just 110 what proportion of the milk must be supplied in pint bottles and just what proportion in half-pint bottles. Heretofore, in order to guard against a possible shortage of boxes for bottles of the smaller size, it has been necessary for the dealer to supply himself with a large number of boxes in excess of those which would probably be needed. By taking advantage of my invention a 115 dealer can order only a small number of boxes for the bottles of the smaller size, or if he so desires, none at all, and by providing himself with a suitable quantity of adapters, transform the boxes normally intended for larger bottles into boxes suitable for the smaller bottles. In this way the dealer can be ready at any time to supply the requisite amount of milk in the smaller bottles without, however, carrying 120 in stock a large number of boxes suitable 125 for the larger bottles. In this way the dealer can be ready at any time to supply the requisite amount of milk in the smaller bottles without, however, carrying 130 in stock a large number of boxes suitable

only for the small bottles. If at any time a box in which the adapters have been placed is no longer needed for the small bottles, it can quickly be made ready for the 5 larger bottles simply by removing the adapters.

What I claim is:—

1. An adapter for a bottle crate having all of its parts firmly connected together and 10 provided with outer walls arranged to engage with the vertical walls of a bottle cell at a plurality of points substantially separated vertically and with inner walls arranged to engage with the vertical walls of 15 a bottle at a plurality of points substantially separated vertically, the said inner walls being substantially separated from the said outer walls whereby the adapter can hold a bottle smaller than that for which 20 the cell is primarily adapted.

2. An adapter for a bottle crate comprising two metallic strips connected to each other at right angles and each bent upward on each side of the point of connection to 25 form an inner vertical bottle-engaging wall and bent outward and downward to form a cell-engaging wall substantially separated horizontally from the inner vertical wall.

3. An adapter for a bottle crate having 30 all of its parts firmly connected together and provided with outer walls arranged to engage with the vertical walls of a bottle cell at a plurality of points substantially separated vertically, with inner walls substantially separated from the said outer walls and arranged to engage with the vertical 35 walls of a bottle smaller than that for which the cell is primarily adapted at a plurality of points substantially separated vertically 40 and with a bottom wall arranged to engage the bottom of a bottle and support it at a level above that of the bottom of the cell.

4. An adapter for a bottle crate comprising two metallic strips connected to each 45 other at right angles and each bent upward on each side of the point of connection to form an inner bottle-engaging wall and bent outward and downward to form a wall for engaging a bottle cell, the downward bent 50 parts of one of the strips extending to a plane below that of the point of connection between the two strips.

5. In combination, a bottle crate having 55 cells with vertical walls, and removable resilient adapters having vertical outer walls arranged to have surface contact with and to be pressed outward against the vertical walls of the cells and inner walls arranged to have surface contact with and to support 60 the vertical walls of bottles smaller than those for which the cells are primarily intended.

6. In combination, a bottle crate having 65 cells with vertical walls adapted for holding bottles of a certain size, and removable

adapters each having all of its parts firmly connected together and provided with vertical outer walls arranged to engage the vertical walls of a cell, with vertical inner walls arranged to engage the vertical walls of a 70 bottle smaller than those for which the cells are primarily adapted, and with bottom walls arranged to support the bottle at a level above that of the bottoms of the cells.

7. The combination with a bottle crate 75 having vertical sheet metal partitions beaded at their upper edges and arranged to form cells for holding bottles of a certain size, of removable adapters formed of resilient material and having outer vertical 80 walls arranged to have surface contact with the walls of the cells below the beads, the adapters being provided with vertical inner walls substantially separated from the outer walls and arranged to engage and support 85 bottles smaller than those for which the cells are primarily intended.

8. The combination with a bottle crate provided with intersecting sets of vertical sheet metal partitions forming cells for bottles of a certain size, the partitions of one set having horizontal flanges at the bottoms of the cells, and with bottle-supporting 90 wires perpendicular to the partitions of the last said set and at the bottoms of the cells 95 which are otherwise open, of removable adapters formed to fit within the cells and provided with downward extending legs adapted to rest on the said flanges, the adapters having inner walls substantially 100 separated from the outer walls and arranged to engage and hold bottles smaller than those for which the cells are primarily intended and with bottom walls arranged to support the bottles well above the plane of 105 the said wires.

9. The combination with a bottle crate provided with intersecting sets of vertical sheet metal partitions forming cells for bottles of a certain size, the lower edges of 110 partitions of one set having horizontal flanges at the bottoms of the cells and the lower edges of those of the other set having beads above the bottoms of the cells, and with bottle-supporting wires at the bottoms 115 of the cells which are otherwise open, of removable adapters formed to fit within the cells and each provided with two pairs of vertical legs, those of one pair being adapted to engage the flanges at the bottom of the 120 cell and those of the other pair adapted to engage the beads above the bottom of the cell, the adapters having inner walls substantially separated from the outer walls and arranged to engage and hold bottles 125 smaller than those for which the cells are primarily intended.

10. The combination with a bottle crate having vertical sheet metal partitions arranged to form cells for holding bottles of 130

a certain size, some of the partitions having beads at their upper edges and some of the partitions having horizontal flanges at their lower edges, of removable adapters formed 5 of resilient material and having outer vertical walls arranged to have surface contact with the walls of the cells below the beads, the said adapters being provided with downward extending vertical legs adapted 10 to engage with and rest upon the said flanges at the bottoms of some of the partitions and with inner walls substantially separated from the said outer walls and the said vertical legs and arranged to engage 15 and hold bottles smaller than those for which the cells are primarily intended.

11. The combination with a bottle crate provided with intersecting sets of vertical sheet metal partitions forming cells for bottles of a certain size, all of the partitions 20 being beaded at their upper edges, the parti-

tions of one set being beaded at their lower edges and the partitions of the other set being provided at their lower edges with horizontal flanges, of removable adapters 25 formed of resilient material and constructed to fit within the cells below the beads at the tops of the partitions, each adapter being provided with inner walls arranged to engage and hold bottles smaller than those 30 for which the cells are primarily intended and with two pairs of legs, one adapted to engage the flanges at the bottoms of the partitions of one set and the other adapted to engage the beads at the bottoms of the partitions of the other set. 35

In testimony whereof I affix my signature, in presence of two witnesses.

GROVER F. BEHRINGER.
